UNITED STATES PATENT OFFICE.

HENRY BLACKFD. PAYNE AND WILLIAM CAMPION, OF NOTTINGHAM, ENGLAND; SAID CAMPION ASSIGNOR, BY MESNE ASSIGNMENTS, TO A. G. JENNINGS & SONS, OF BROOKLYN, NEW YORK.

MACHINE FOR LACING JACQUARD CARDS.

SPECIFICATION forming part of Letters Patent No. 395,076, dated December 25, 1888.

Application filed March 22, 1888. Serial No. 268,074. (No model.) Patented in England January 30, 1886, No. 1,397.

To all whom it may concern:

Be it known that we, HENRY BLACKFORD PAYNE and WILLIAM CAMPION, both of Nottingham, England, have invented an Improved Jacquard Card-Lacing Machine, of which the following is a specification, and for which we have obtained Letters Patent of Great Britain, No. 1,397, dated January 30, 1886.

10 Our invention has for its object to provide a machine that will lace together with a single thread cards for Jacquard knitting-machines, looms, and the like.

15 The invention consists in the details of improvement and the combinations of parts, that will be more fully hereinafter set forth.

Reference is to be had to the accompanying drawings, forming part of this specification, in which—

20 Figure 1 is a side elevation of a machine constructed according to our invention. Fig. 2 is a plan view of the same, partly broken. Fig. 3 is a vertical cross-section, enlarged, taken on the plane of the line *c c*, Fig. 2. Fig. 25 4 is a detail section on the line *k k*, Fig. 3. Fig. 5 is a detail side elevation of the machine, looking from the side opposite that shown in Fig. 1. Figs. 6 and 7 are detail face and edge views, respectively, of the cam for operating 30 the looper-shaft; and Fig. 8 is a face view of a portion of two cards shown sewed together.

In the accompanying drawings, A represents the framing of our machine, which may be of suitable construction. In the upper 35 front portion of the frame A is journaled a horizontal shaft, B, that receives motion by means of belt and pulley or other suitable gear. In the upper rear portion of the framing A is hung a rod, D, parallel with the shaft B.

40 Upon the shaft B and rod D, or upon suitable portions of the frame A, are hung two or more lacing-machines proper, that are adapted to be moved longitudinally along the framing A toward and from each other. These lacing-45 machines proper are arranged and operate as follows: F is the bed-plate of one such lacing-machine proper, over which extends an arm, G. The bed-plate F has downwardly-extending brackets *a*⁶ at both ends, through which 50 loosely pass the shafts B and rod D, and by

this means it is supported. The bed-plate F, carrying the arm G, is thus permitted movement along the shaft B and rod D. A suitable set-screw, *a*⁷, carried by the rear bracket, *a*⁶, and that is adapted to bear upon the rod 55 D, serves to hold the bed-plate F and all its attachments rigidly in its proper position. The bed-plate F and the arm G carried thereby constitute the main portions of the lacer.

Through each arm G of the separate lacers 60 passes a continuous rock-shaft, *a*, that may also be supported at its ends by brackets *b*, extending from the framing A. The shaft *a* carries at its ends cranks *d*, that are connected by links *e* with eccentrics *f f* on a cam-shaft, 65 H, that is suitably journaled in the framing A. The shaft H is placed below the bed-plate F of the lacers. The shaft H is rotated from the shaft B by means of gearing *g h*, or otherwise. By the above construction, as the 70 shaft B rotates, the shaft *a* will be rocked in its bearings. The shaft *a* carries a crank or lever, *i*, for each lacer. To the free end of each lever *i* is pivoted a needle-bar, *j*, that is guided in a suitable head or frame, I, on the 75 end of the corresponding arm, G. (See Fig. 3.) Each needle-bar *j* carries a needle, *l*, that passes through the bed-plate F, as in ordinary sewing-machines. Each lever *i* also carries another rod or bar, *m*, parallel with the needle-bar *j*, in the end of which bar *m* is secured a punch, *n*, that is adapted to pass into or through a die or matrix, *o*, which is carried by the bed-plate F, and in its passage to perforate a card, J, on the bed-plate F above said 85 die. The rod *m* and punch may be in one piece, if desired. The punch-rod *m* also carries on a projection, *m*², a card-holding rod, *p*, that is situated between the needle and the punch *n*, as clearly shown in Fig. 3. The 90 lower end of this rod *p* extends below the punch *n* and is adapted to enter the last hole made in a card, J, by the punch *n*, to hold said card as the punch *n* acts to perforate it. Said rod *p* enters a die, *o*², on the bed-plate F. The 95 needle *l* is adapted to pass through the hole made in the card J by the punch *n*. The cards J are held on the bed-plate F, so as to be operated upon by the punch *n* and needle *l* by means of a presser-foot, *q*, that is carried 100

by a rod, r , passing through the head I. This presser-foot q is of such length as to hold a number of cards J at once, as shown in Fig. 3.

- To enable the punch n to be adjusted toward or away from the needle l , we provide the head I with suitable guide-blocks, s s , through which the punch-bar m passes. These guide-blocks s s are carried in slots s^2 in the head I, and are provided with screws t , that pass through slots u in the side of the head I and hold said blocks s in position. The support of the punch-rod m also passes through a slot, s^1 , in the lever i , as shown in Fig. 3, or is otherwise arranged for permitting the adjustment of the rod m . The die or matrix o is also movable with relation to the punch n . For this purpose the die o is held between a plate, v , and the bed-plate F by screws w , which screws pass through slots x in the die. (See Fig. 4.) These slots permit the adjustment of the die o , while the screws w and plate v hold it in position. When the length of stitch is varied—or, in other words, the distance between the holes punched in the card by the punch n is varied—the distance between the punch and the rod p should also be varied to meet such change. For this purpose the projection m^2 on the punch-bar m is slotted to receive the end of the bar p , which bar is held in position by a nut or otherwise. The die o^2 for the rod p is also adjustable by means of a slot, y , in an arm of the die o^2 and a screw, z , as shown.
- L is the feeding-rack for passing the cards J from the punch n to the needle and away from the needle. The feeding-rack L is forked beneath the presser-foot q and passes through slots in the bed-plate F. (See Fig. 4.) The rack L may be actuated by suitable means; but we prefer the following: The rack L is secured at its outer end to a reciprocating block, M, that is supported on a pivot, a^2 , at the front of the bed-plate F. The pivot a^2 passes through a slot, b^2 , within the block M. Within said slot b^2 is placed a spring, d^2 , that bears at one end against the pivot a^2 and at its other end against the block M, which spring acts to press the block M inward, thereby carrying the feeding-rack inward. A set-screw, e^2 , in the end of the block M, limits its inward motion. The feeding-rack L is elevated to grip the cards J by means of a cam, N, on the shaft H, which cam N bears against a projection or contact-face, f^2 , on the feeding-rack. The feeding-rack L is moved toward the front of the machine to feed the cards by means of a cam, O, on the shaft H, which cam bears against a shoulder, g^2 , or surface on the block M or on the feeding-rack. The cams N and O are so adjusted on the shaft H that after the spring d^2 has moved the feeding-rack L inward under the cards the cam N will first act upon the projection f^2 to raise the rack L against the cards, when the cam O will immediately press against the shoulder g^2 to advance the rack, and thereby

the cards. The cam N will then allow the feed-dog to descend, the cam O at this time permitting the rack L to be moved inward by the spring d^2 .

70

The cards J are to be arranged in a pile behind the head I and contiguous to an upright or wall, h^2 , that is over the bed-plate F. The lower edge of this wall h^2 is to be at such a distance above the bed-plate F as to permit one card at a time to be pushed under it to be engaged by the feeding-rack L.

75

The cards J may be suitably fed one by one to the feeding-rack L and the punch n , but are preferably fed by means of a plunger or feeding-plate, i^2 . The plunger i^2 passes over the bed-plate F, under a cross-bar, j^2 , and against the lower card J of the pile, to push said card beneath the wall h^2 between the presser-foot q and punch n . The plunger i^2 of each lacer connects with a rod, l^2 , that is secured to cranks n^2 on a horizontal rock-shaft, p^2 , journaled in the framing A. The shaft p^2 is actuated from a shaft, q^2 , that is journaled in the framing A in proximity to the shaft p^2 . The shaft q^2 carries a cam, r^2 , and a counter-cam, t^2 , as clearly shown in Fig. 1. The cam r^2 bears against a crank, u^2 , on the shaft p^2 , while the counter-cam t^2 actuates a crank, v^2 , on said shaft p^2 . The shaft q^2 carries at one end a disk or enlargement, u^2 , upon which are arranged a number of pins, x^2 . (See Fig. 5.) The pins x^2 are engaged alternately by a claw-lever, y^2 , that is pivoted to the eccentric f on the shaft H. Said lever y^2 , as the shaft H rotates, draws upon one pin x^2 at each revolution of the shaft H to partially turn the shaft q^2 , and by this means intermittent rotary motion is imparted to the shaft q^2 .

105

The position and action of the cams r^2 t^2 on the shaft q^2 is such that as the narrow part of the cam r^2 comes opposite the crank u^2 the cam t^2 will bear upon the crank v^2 , as in Fig. 1, to rock the shaft p^2 and push the plunger i^2 forward to feed a card J to the punch n and needle l . As the shaft q^2 receives its next movement by the lever y^2 and a pin, x^2 , a wide part of the cam r^2 will press upon the crank u^2 to turn the shaft p^2 in the reverse direction to its last movement, thereby withdrawing the plunger i^2 from beneath the pile of cards and permitting the lower card of the pile to pass in front of the plunger, ready to be pushed forward to the punch n . During each subsequent motion of the shaft q^2 by its lever y^2 and pins x^2 , until the narrow part of the cam r^2 again comes opposite the crank u^2 , as before stated, the plunger will remain in the rearward non-operating position. Thus where five pins x^2 are used, as shown in Fig. 5, one pin acts to turn the shafts q^2 p^2 , to move the plunger i^2 forward to push a card, the next to turn the shafts q^2 p^2 to move the plunger rearward, while the other three pins merely act to turn said shaft q^2 without actuating the plunger. After a card is pushed

115

120

125

130

forward by the plunger i^2 , the feeding-rack L moves the card step by step to the punch n and to the needle l.

Although we have shown five pins x^2 , whereby the shaft q^2 will receive five intermittent motions to one revolution of the cam-shaft H, the number of pins, and thereby the number of motions of the shaft q^2 , may be varied according to circumstances. If preferred, a spring could be used to actuate the crank v^2 in place of the counter-cam f^2 . The plunger i^2 may be made adjustable in length from the rod l^2 to its outer end, so as to actuate cards of different widths to place said cards in proper position to be engaged by the feeding-rack L.

Having seen how the cards are fed and that the holes are punched therein by the successive descents of the punch n for the passage of the needles, we will now show how the cards are laced together.

Each time a hole is punched in a card by the punch n said card is fed forward a certain distance by the rack L until said hole comes in line with the needle. As the needle l and punch n descend in unison, the needle will pass through a hole in a card while the punch is making another hole for the needle. The needle l carries a thread, a^4 , Fig. 1, through the hole in the card made by the punch and below the bed-plate, where the thread is caught by a looper, P, Fig. 3, that is carried by a rock-shaft, Q, journaled in the framing A. The shaft Q is adjacent to and parallel with the cam-shaft H. The shaft Q receives a rocking motion to cause the looper P to take the thread from the needle by means of a cam, R, on the cam-shaft H. (See Fig. 2.) The cam R, by its periphery, acts on a crank, b^4 , on the shaft Q to rock said shaft. A counter-cam, R^2 , on the shaft H acts on a crank, d^4 , to return the shaft Q and thereby the looper; but a suitable spring may be substituted for the counter-cam R^2 . The shaft Q also receives a longitudinal motion in one direction by the cam R acting on its side against the crank b^4 . The side of the cam R for this purpose is clearly shown in Fig. 7. The shaft Q receives longitudinal motion in the reverse direction by means of a spring, d^4 . (See Fig. 2.) This longitudinal and rocking motion of the shaft causes the looper to take a loop from the receding needle and to place it in such position that the needle will pass through the loop on its descent. The looper then recedes and releases the loop, leaving it on the needle. The looper then returns to take another loop from the needle. Thus a continuous series of loops is formed; but although we have shown a particular form of looper, we wish it understood that we may use any desired looper to act with the needle to lace the cards. The needle l not only passes through each hole made by the punch to form a loop, but also passes between two cards to there form a loop, and thus connect the cards together; or, in other words, the needle passes through

the last hole in a card to form a loop, then passes along the edge of the card and between that and the next card to form a joining or connecting loop, and then into the first hole in the next card. Suitable guides, S, Fig. 1, and tension devices may be used for the thread a^4 in its passage to the needle.

Having heretofore explained the separate operations of the different parts of the machine, we will now show how the machine operates as an entirety.

It will be remembered that there will be two or more lacers proper mounted on the framing A, each one being constructed substantially as shown. Suppose a series of cards J are to be laced in three places, say, at the ends and in the middle. Three lacers will then be used (only two being shown in Fig. 85 2) and will be moved along the framing A until in their proper positions with relation to the cards J. The cards J will be placed in a pile, as shown in Fig. 3. The machine is now started by revolving the shaft B. The shaft a will thereby be rocked, causing the needle l, punch n, and holding-rod p to rise and fall at the proper speed. The plunger i^2 will now act to push a card J from the pile of cards and up to the punch n. The next movement of the plunger will be to retreat from the cards. In its first downward movement the punch n will pass along the edge of the card that was just pushed forward by the plunger. As the punch rises, the feed-dog L 100 will act to push the card forward a certain distance under the punch. At the next descent the punch n pierces the card, the holding-rod p passing along the edge of the card to steady it. The punch now rises and the card is fed forward. In its next descent the punch pierces the card, the rod p passing through the previously-made hole in the card, and the above operations are repeated. When the card reaches the needle l, said needle will 110 pass through the hole made by the punch n. The loop will then be formed, and when the needle retreats the card will be moved forward to bring the next hole under the needle. After the last hole has been made in the card 115 said card will be moved forward and the punch will then descend along the edge of the card. At the next forward motion of the last card a new card will be pushed up to the punch by the plunger, when the motion is repeated. 120 All the cards on the rack L are moved in unison, the needle l entering every hole made by the punch to form a loop, also forming a connecting loop or hinge between every two cards. The different lacers that are lacing a card are 125 so adjusted that all the same parts move in unison, and thus the cards are passed from the lacing-machine properly sewed together in two, three, or more places.

The cams N O and looper P are to be attached to their respective shafts, so as to be longitudinally adjustable thereon.

By first punching holes in the cards for the passage of the needle we are enabled to sew

the cards by machinery, and to use a single thread in each row of stitches, which is a great saving in time and material over cards that are sewed together by hand, or where a braid is used to attach card to card. Cards connected by our improved lacing-machine are not liable to become separated, and retain their proper position.

It is evident that the means for rocking the shaft a , also the shafts p^2 and Q , may be altered without departing from our invention; but we find the construction shown to be satisfactory.

Having now described our invention, what we claim is—

1. The combination of the punch n , needle-bar j , needle l , rod p , looper P , and feed-rack L with one another, and with means, substantially as described, for moving the feed-rack to feed a card the exact distance between the punch n and rod p , so as to enable said rod to enter the holes made by said punch, and with mechanism, substantially as described, for moving the rod p through the card, as set forth.
2. The combination of the punch n , holding-rod p , needle-bar j , needle l , feed-rack L , means, substantially as described, for actuating them, and looper P , with the plunger i^2 , for passing a card to the punch, and with means, substantially as described, for actuating said plunger, as specified.
3. The needle-bar j , needle l , punch n , lever i , supporting them, rock-shaft a , carrying said lever i , and crank d , for rocking said shaft, in combination with the plunger i^2 , for feeding a card to the punch, and with looping mechanism, substantially as described, for forming loops from the needle, as specified.

4. The combination, with punching and lacing mechanism, substantially as described, of the plunger i^2 , crank n^2 , shaft p^2 , and crank u^2 , with the shaft q^2 , cam r^2 on said shaft for engaging the crank u^2 , and means, substantially as described, for imparting intermittent rotary motion to the shaft q^2 , as specified.

5. The combination, with punching and lacing mechanism, substantially as described, of the plunger i^2 , rock-shaft p^2 , connected therewith, shaft q^2 , cam r^2 thereon for actuating the shaft p^2 , pins x^2 on the shaft q^2 , lever y^2 for said pins, and eccentric f , for actuating said lever, substantially as described.

6. The cam-shaft H and double cam R , carried by said shaft, combined with the looper rock-shaft Q , having crank b^1 , that is actuated both by the periphery and side of the cam R , and the looper P on said shaft Q , as specified.

7. The combination of the needle-bar j , needle l , lever i , and rock-shaft a , supporting said lever, with the head I , adjustable guide-block s in said head, and punch-rod m , passing through said block s and carried by the lever i , substantially as described.

8. The frame A , having shaft B and rod D , combined with the adjustable laces carried thereon and movable along said shafts, each lacer carrying punch and stitch-forming mechanism, and with mechanism, substantially as described, for operating said punch and stitch-forming mechanism, as specified.

The above specification signed by us this 6th day of January, 1888.
